UNITED STATES PATENT OFFICE.

JOSEPH W. HELTZEL, OF WARREN, OHIO.

CONCRETE MIXER.

Application filed July 17, 1920. Serial No. 396,990.

To all whom it may concern:

Be it known that I, JOSEPH W. HELTZEL, a citizen of the United States, residing at Warren, in the county of Trumbull and 5 State of Ohio, have invented a new and useful Concrete Mixer, of which the following is a specification.

This invention relates to agitators and more particularly to an improved concrete 10 mixer adapted to be manually operated to mix various ingredients such as concrete or the like, the device being constructed to be manually manipulated to mix a maximum quantity of concrete by hand in the shortest 15 possible time consistent with a device or machine of its type adapted to be manually manipulated, and which is relatively inexpensive and durable.

A further object of the invention is to provide 20 an improved concrete mixer of the type employing a movement on the principle of the walking beam in combination with an actuating cable and drum therefor, so as to oscillate a mixing drum or receptacle of elongated form, whereby the water may be 25 caused to drop first and then the aggregate and other heavy contents on top of the water, thus obtaining a thorough and rapid mixing with a minimum of labor.

30 A further object of the invention is to provide an improved concrete mixer having a novel construction of mixing drum supported for oscillation together with improved means for actuating the same and for charging and filling and emptying the contents of the drum after the same has been mixed.

With the above and other objects in view which will appear as the description proceeds, the invention resides in the combination 40 and arrangement of parts and in the details of construction hereinafter described and claimed, it being understood that within the scope of what is claimed, changes in the precise embodiment of the invention 45 shown can be made without departing from the spirit of the invention.

In the accompanying drawings:

Figure 1 is a side elevation of my improved concrete mixer;

50 Figure 2 is a longitudinal sectional view thereof vertically of the mixer;

Figure 3 is an end elevation; and

Figure 4 is a vertical sectional view taken on the line 4—4 of Figure 1.

55 Referring to the drawings in detail, in

which like reference characters designate corresponding parts throughout the several views, my improved mixer is shown as comprising an elongated receptacle or drum 10 preferably of tubular outline and cross-section, mounted intermediately of its ends upon a transverse pivot or rocker shaft 11 forming a pin or trunnion which supports the mixing drum and which may extend entirely through the drum or otherwise, as desired. 60 The ends of this shaft or trunnion are rotatably mounted in a frame structure including spaced uprights or supporting posts 12 which are arranged in spaced parallel relation upon a base or supports 13 and held 65 rigidly in such position through the medium of oppositely inclined diagonal braces 14 extending between said uprights and the base near the outer ends of the latter. The base includes transverse connecting or end members 15 so as to render the structure rigid 70 and to connect the side members forming the base proper.

A pair of posts 16 extend from the base 75 near the lower ends of the uprights at right angles to the braces 14 and extend upwardly beyond the point of intersection, where the upper extremities of said limit or stop posts are recessed, as indicated at 17 for a purpose 80 to be hereinafter more particularly specified. 85 Adjacent to the posts 16 and connected thereto and to the braces 14 are transverse connecting members 18 forming blocks or supports for sheaves or pulleys 19, rotatably mounted in brackets 20 carried by said supports upon the upper faces thereof, preferably 90 below the posts.

At the sides of the drum or receptacle, there are disposed strips 21 which reenforce 95 and strengthen the drum to form bearings for receiving the shaft or trunnion 11, said strips being preferably riveted or otherwise secured at the opposed sides of the drum so as to extend longitudinally thereof for a considerable distance. The top of the drum 100 is provided with a reenforced opening 22, a stiffening ring 23 being disposed around the edge of the opening, and suitably riveted to the drum for this purpose, and said opening being located centrally of the length of the 105 drum as shown. The drum may be further provided with an opening 24 which may be closed by a hinged or other cover 25 having a suitable fastening means 26, it being understood that the drum is charged through 110

the opening 22 when the device is in a horizontal position, or may be charged through the opening 24 when the drum is in an inclined position toward the end opposite to that provided with the opening 24, so that the end at which this opening is provided is uppermost and the opposite end lowermost. The cover is of course closed when the device is in use, as it is thought will be obvious.

One end of the drum is provided with a permanent wall 27 and the opposite end is provided with a hinged closure or end 28, hinged at the top, as indicated at 29, the end 27 being permanently secured in position and the hinged end or end piece 28 being adapted to cooperate with a packing member 30, so that a liquid tight joint is formed at said end. That is, the upper portion of the end piece is fixed, while the lower portion is designated at 31 so that the contents may be discharged from the bottom thereof.

At the lower portion of the discharge door 31 or end, the latter is provided with a lug 32 adapted to swing therewith and made in the form of a catch adapted to be engaged by the adjacent end of a locking lever 33 pivoted intermediately as shown at 34 upon a bracket 35 secured to the bottom of the drum. The locking lever is held into engagement with the lug through the medium of an expansible helical spring 36 which is mounted on a bolt or pin 37 projecting downwardly from the drum and carrying a limit nut or stop 38 restricting the downward movement of the lever at the inner arm thereof, it being observed that the lever is pivoted intermediately of its end, and nearer the outer end thereof than the inner end thereof, so that the inner arm is longer than the outer whereby but slight movement of the lever is required in moving to and from an engaging or disengaging position. The longer arm of the lever at its inner end is adapted to engage and rest upon a releasing lever 39 pivoted as shown at 40 to a bracket 41 also suspended beneath the drum like the bracket 35, the inner end of the lever 39 forming a hand hold by which the longer arm of the lever 33 may be elevated against the action of the spring 36, in order to release the locking end of the lever from the lug or catch 32, whereby the swinging discharged door 31 may swing to an open position or be locked in a closed position and held thereby.

In order to actuate the mixing device, that is, to oscillate the mixing drum or receptacle, there is provided a drum or winding device 42 between the uprights 12 about midway between the bottom of the drum and the base of the supporting frame, the same having an operating crank or handle 43 by

which it may be actuated, said device being located at one side of the frame in position for convenient manipulation for oscillating the drum 42. Engaged around the drum 42 is a cable 44, the same extending in opposite directions and trained beneath the sheaves or pulleys 19 and having their free ends connected to the extremities of the mixing drum or receptacle 10 through the medium of yokes 45 secured to and suspended beneath the same. One of the yokes is adapted to extend around the locking lever and adjacent parts so as to not interfere with the operation of the latter, it being understood that said yokes are rigid and the connection of the extremities of the cables therewith is made through the medium of rings or links 46, with interposed compensating connections or springs 47, in order to take up jar and shock, as the drum 10 is oscillated and as the same changes its motion from one side to the other.

In the operation of the device, the drum is filled with the material to be mixed, preferably water first and then the concrete, gravel, sand or other material to be thoroughly agitated and intermixed, through the opening 22, the closure 25 and the swinging discharge door 31 being closed. The interior of the drum is provided with a series of spaced baffle blades 48, preferably sloping in one direction toward the discharge door 31, so that with the water placed beneath the aggregate and other heavy contents, the water will drop first and then the aggregate, thus securing a thorough and rapid mixing with a minimum of labor, by merely agitating the contents through the medium of oscillation of the mixing cylinder by turning the hand crank and its drum in opposite directions to the desired extent. This oscillatory movement is regulated by engagement of the stop posts 16 at their concaved ends 17 with the drum, it being understood that said concaved ends are made to conform to the contour of the drum in order to limit the oscillatory movement of the drum or its incline at either side. It is of course to be understood that when the hand crank or crank handle and the drum 42 thereof is manipulated, the cable will be wound in one direction and unwound in the other, this causing the mixing the drum or receptacle to be oscillated in the manner of a walking beam through the medium of the extremities of the cable connected to the extremities of the mixing drum as described. When the mixing operation is completed, the drum is moved to an inclined position and may be provided with a further mixture, in order that the concrete may be sufficiently dry and yet sufficiently wet, if the same is not in the proper proportion or condition. If the mixture is correct, the discharge door may be opened to discharge

the contents, and otherwise, the mixing operation must be continued after closing the cover 25, the required additional materials having been previously charged there-
5 through. It will of course be understood that the inclined baffle blades 48 by being set at an angle, will not interfere with the thorough mixing of the ingredients and discharge of the contents through the discharge
10 door at one end of the mixing drum or receptacle, but will catch the material as the drum is oscillated in either direction, owing to the positioning of said blades at the bottom of the drum or cylinder, so as to churn
15 the concrete when dropping from one end of the cylinder to the other so as to insure thorough agitation. In connection with the foregoing, it may also be stated that the winding device comprised by the drum 42,
20 the cable 44 and the shank handle 43, constitutes a simple embodiment of the actuating means for the mixing drum, cylinder or receptacle, it being understood that the winding drum 42 is mounted on a shaft 49
25 rotatably journaled in the side members or uprights 12, the crank handle being secured to the shaft so that the same may be manipulated to impart oscillatory movement there-
30 to for alternately winding the drum in one direction while the other end is being unwound, and then winding the cable on the drum in the opposite direction while the opposite end is being unwound, thus exerting
35 opposite pull alternately on the ends of the mixing drum or cylinder to cause the latter to rock at either side and in oppositely in-

clined positions limited by the stop or limit posts 16 as heretofore specified.

It will thus be seen that I have provided a very simple and efficient form of manually operated concrete mixer which requires but a small expenditure of power to manually manipulate the same, and which owing to the length of the mixing drum, cylinder or receptacle, may be made to have a relatively 40 large capacity and yet thoroughly intermix the contents in a very short time. While I have shown and described the form of the invention which now seems to be the preferred embodiment thereof, I desire to have 45 50 it understood that I may make such changes in the construction thereof, as will be found covered by the device as set forth in the appended claim.

Having thus described the invention what 55 I claim is:

In a mixing device, a support, a drum pivotally mounted intermediate its ends to permit the same to oscillate, a plurality of semi-circular spaced baffle blades positioned 60 within the drum, the upper ends of the baffle blades terminating at points intermediate the top and bottom of the drum and means for oscillating the drum.

In testimony that I claim the foregoing as 65 my own, I have hereto affixed my signature in the presence of two witnesses.

JOSEPH W. HELTZEL.
